Patented Feb. 28, 1922.

UNITED STATES PATENT OFFICE.

SAMUEL ARNOLD, 3d, OF BEN AVON, PENNSYLVANIA.

COLLECTOR-LIFTING MECHANISM.

1,408,158.

Specification of Letters Patent. Patented Feb. 28, 1922.

Application filed September 22, 1921. Serial No. 502,376.

To all whom it may concern:

Be it known that I, SAMUEL ARNOLD, 3d, a citizen of the United States, and resident of Ben Avon, in the county of Allegheny and State of Pennsylvania, have invented certain new and useful Improvements in Collector-Lifting Mechanisms, of which the following is a specification.

This invention relates to trolleys for electrically operated traveling cranes, cars and the like, and more particularly to means for lifting the collectors of such trolleys free from the electrical conductors from which the operating current is received, and has for its object the provision of a novel trolley construction that will embody such means.

In electrically operated traveling cranes and the like it is common to have a trolley with a plurality of collectors thereon for receiving the electric current necessary to operate the various lifting and other crane elements, such collectors being independent of the main collectors used to receive the electric current necessary to move the crane along its track. Where collectors have been mounted on a trolley as stated, for receiving the current necessary to operate the lifting and other crane elements, they have heretofore been constantly in contact with their respective conductors which are rigid. Such a construction subjects the collectors to continuous wear, and consequently they must be frequently renewed.

With a trolley constructed according to this invention the collectors need only contact with the conductors when actually in use to complete a circuit. Therefore unnecessary wear is eliminated and the life thereof is materially lengthened.

With the above objects and advantages in view, the invention is described in the following specification and illustrated in the accompanying drawings, in which—

Figure 1 is a side elevation of a trolley embodying my invention.

Figure 2 is a sectional plan, on the line II—II of Figure 1.

Figure 3 is a partial rear elevation of the trolley, showing the counterweighted lever connection.

Referring more particularly to the drawings, the numeral 2 designates the trolley base to which the upright trolley member is secured, and which forms a permanent part of the crane or other vehicle to which the trolley is to be secured.

The trolley member is composed of angle iron side members 3 and 4 which are secured together in spaced relation by back plates 5 and 6. The side flanges of the members 3 and 4 form a guideway or channel for a vertically movable collector support A, which is composed of a T-shaped center member 7, formed by securing two angle members together back to back, as is clearly shown in Figure 2, and insulator side members 8 which are secured to the center member 7 by bolts 9. The back flanges 10 of the T-shaped member 7 are adapted to abut the back plate 6 of the trolley when the collector support A is in its extreme up position.

The forward edges of the side members 8 are secured together in spaced relation by bolts 11 which have spacing washers 12 thereon, and have collars 13 on each end which project an appreciable distance beyond the side members 8. A plurality of U-shaped collectors 14 is pivotally mounted on bolts 15 which pass through the side members 8 and center member 7. The bolts 15 have an insulating sleeve 16 thereon to prevent current from the collectors passing through the bolt and to the metal center member 7.

The collectors are adapted to normally rest and ride upon conductors 17 which may be of any well known construction, although they are generally in the form of angles as shown, and are secured by insulators 18 to supports 19.

The collector support A is movably secured at its upper end to the trolley member by links 20 which are pivotally secured at one end to a bolt 21. The bolt 21 passes through the angle supports 22, which are secured to the back to back flanges of the center member 7, and the insulator side members 8. The links 20 are inclined rearwardly and downwardly and have one end mounted on a bolt 23 which is secured in angle brackets 24 that are fastened to the back plate 6 of the trolley.

The lower end of the collector support is provided with a pair of downwardly projecting spaced plates or ears 25 which are secured to the center member 7 and provide a mounting for the forward end or arm 26 of a bell crank lever X, which is pivoted at its elbow or crank portion on a bolt 27 secured in the side flanges of the members 3 and 4 of the trolley. The other arm 28 of the crank lever projects rearwardly and sidewardly and is pivotally connected to

a link 29, which has its lower end pivotally connected to one arm 30 of bell crank lever Y, which is pivotally mounted at its crank or elbow portion 31 to a support 32 located 5 in a crane cab or other such location readily accessible to the operator. The other arm 33 of the bell crank lever Y has a hand grip 34 thereon, and forms an operating lever. The lever 34 has a spring pressed latch 35 thereon adapted to lock the bell crank Y in its adjusted position, so as to positively 10 position the collectors and collector support.

The bell crank lever X has a counter-weight lever 36 extending rearwardly on a 15 line with the arm 26 and provided with an adjustably positioned counterweight 37.

When it is desired to raise the collectors 14 out of contact with the conductors 17, the operator will rock the bell crank lever 20 Y thus pulling on the link 29 and rocking the bell crank lever X which will lift the collector support A upwardly and backwardly against the back plates 5 and 6. As the collector support A is raised the collars 25 13 on the bolts 11 will engage the pivoted collectors and cause them to lift with the support.

A stop member 39 is secured to the back flanges 10 of the center member 7 of the 30 collector support and is adapted to abut the top edge of back plate 5 of the trolley member to limit the downward movement of the collector support.

The operation of this improved trolley and 35 collector lifting mechanism and its many advantages will be readily apparent to those skilled in the art.

It will be understood that although only one specific embodiment of the invention is 40 shown and described, various modifications may be made without departing from the scope of the invention as defined in the appended claims.

I claim:—

45 1. The combination with a rigid trolley member, of a collector support slidably mounted on said trolley member, at least one collector pivotally mounted on said support adapted to normally contact with a

suitable conductor, stop members projecting 50 from said support for limiting the downward movement of said collector, and means for raising said collector support and said collector to break the contact with said conductor.

55 2. The combination with a rigid trolley member, of a collector support slidably mounted on said trolley member, at least one collector pivotally mounted on said support adapted to normally contact with a 60 suitable conductor, stop members projecting from said support for limiting the downward movement of said collector, and a lever mechanism for moving said collector support and said collector vertically relative to said 65 trolley to break the contact of said collector with said conductor.

70 3. The combination with a rigid vertically disposed crane trolley member, of a collector support adapted to have a limited vertical movement relative to said trolley, a plurality of collector members pivotally mounted on said collector support adapted to normally contact with suitable electrical conductors, and a counterweighted lever mechanism for 75 simultaneously moving said collector support and said collectors vertically relative to said trolley to break the contact of said collectors with said conductor.

80 4. The combination with a rigid vertically disposed crane trolley member, of a collector support adapted to have a limited vertical movement relative to said trolley, a plurality of collector members pivotally mounted on said collector support adapted 85 to normally contact with suitable electrical conductors, stop members projecting from said support for limiting the downward movement of said collectors, and a counterweighted lever mechanism for simultaneously moving said collector support and said collectors vertically relative to said 90 trolley to break the contact of said collectors with said conductor.

95 In testimony whereof, I have hereunto signed my name.

SAMUEL ARNOLD, 3d.
